CLAIM

I claim the ornamental design for a paint scraper set, as shown, and described.

DESCRIPTION

FIG. 1 is a perspective view of the first embodiment of the paint scraper showing my new design wherein the handle is aligned to the blade;

FIG. 2 is a top view of the paint scraper thereof;

FIG. 3 is a bottom view of the paint scraper thereof;

FIG. 4 is a left-side view of the paint scraper thereof;

FIG. 5 is a right-side view of the paint scraper thereof;

FIG. 6 is a front-side view of the paint scraper thereof;

FIG. 7 is a back-side view of the paint scraper thereof;

FIG. 8 is a perspective view of the second embodiment of FIG. 1;

FIG. 9 is a top-side view of the paint scraper shown in FIG. 8 thereof;

FIG. 10 is a bottom-side view of the paint scraper shown in FIG. 8 thereof;

FIG. 11 is a right-side view of the paint scraper shown in FIG. 8 thereof;

FIG. 12 is a left-side view of the paint scraper shown in FIG. 8 thereof;

FIG. 13 is a front-side view of the paint scraper shown in FIG. 8 thereof; and,

FIG. 14 is the back-side view of the paint scraper shown in FIG. 8 thereof.

The ornamental design which is claimed is shown in solid lines in the drawings. The broken lines in the drawings are for illustrative purposes only and form no part of the claimed design. Broken lines formed by equal length dashes show unclaimed subject matter.
